METHOD AND APPARATUS FOR MANUFACTURING FLUORESCENT LAMPS

Harold D. Blake and Wilford J. Winninghoff,
Cleveland Heights, Ohio, assignors to General
Electric Company, a corporation of New York

Application September 6, 1946, Serial No. 695,264

17 Claims. (Cl. 316—1)

1

Our invention relates to methods and apparatus for manufacturing electric fluorescent lamps and similar electric devices. More particularly, our invention relates to methods and apparatus for performing the heat-produced sealing-in and baking operations and then the exhausting and filling operations in the manufacture of electric fluorescent lamps.

Operations in the manufacture of the common form of fluorescent lamp provide for the application of a coating containing a fluorescent material to the lamp bulb, the baking or heat treatment thereof to separate the binder from the coating, the further heating of the lamp parts in the sealing-in of electrode mounts to the ends of the bulb, and the exhaustion of the lamp. With this combination of operations are also included for convenience, the operations of heat treating the lamp to release the occluded elements therein, heating of the cathode of the lamp to cause activation thereof and filling of said lamp with an ionizable gas and discharge supporting materials. All of the manufacturing operations have been performed in relatively large automatic machines heretofore which machines permit the more favorable grouping of the operations and which give the fineness and uniformity of control necessary for successful completion of said operations. The grouping of the operations has to a certain extent been formulated with regard to the convenience of making such high speed automatic machines and to other manufacturing problems and has burdened the manufacture with a procedure in some ways detrimental to the lamp.

One object of our invention is to provide methods and apparatus for manufacturing fluorescent lamps which avoid contamination of the fluorescent coating and the interior parts of an electric fluorescent lamp during the course of manufacture. Our invention provides a particular sequence of lamp making operations which greatly reduces the possibility of contamination of the lamp parts by the absorption, condensation and deposition of gases, water vapor and other foreign material thereon. The methods are particularly characterized by the requirement that the fluorescent coating, which is applied to the inner surface of the bulb prior to the sealing of the electrode assemblies thereto, be heat treated during the exhaustion of the lamp or immediately prior thereto. By heat treating the fluorescent coating at such times, the period of time during which the finally treated coating is exposed to contamination is materially reduced and said coating is more effectively closed off from con-

5 taminating elements until the lamp is finally sealed. The method of operation eliminates the heating of the bulb in a period when any subsequent cooling can cause air and contamination to be drawn into it.

Another object of our invention is to provide a method and apparatus having a continuous sequence of lamp manufacturing operations which allows manufacture of a fluorescent lamp of higher efficiency and of greater efficiency maintenance throughout the life thereof. The present advantages of our invention are realized, apart from a reduction in the contamination in the lamp, in a reduction in oxidation etc. of the fluorescent coating and the elimination of any re-absorption in said coating of gases driven off during the heat treatment. The lamps pass rapidly through the manufacturing operations which are arranged so as to reduce the period of time for contamination and other injurious effects to take place to an absolute minimum and permit the exhaustion and development of a controlled atmosphere about the lamp parts to reduce more effectively said contamination and injurious effects.

20 25 Our invention also prevents the condensation of the products separated by the heat treatment from the fluorescent coating and other lamp parts on the surface of all parts of the lamp and the complex interstices of manufacturing apparatus.

30 35 Another object of our invention is to provide a method and apparatus for the more economical manufacture of fluorescent lamps. Our present object realizes a saving in time in the manufacture of the lamp by reducing the number of separate steps taken therein and, in certain instances, by decreasing the time required for said steps. A reduction in the amount, size and cost of the manufacturing apparatus is also realized as well as a considerable saving in labor, fuel and floor space. According to our invention a single heat treatment serves to condition the fluorescent coating and to condition the lamp parts in the manner usually associated with the exhausting operation in the manufacture of the lamp.

40 45 50 A still further object of our invention is to provide a method and apparatus affording more ready and accurate control of the time and temperature elements of the heat treating operation in the manufacture of a fluorescent lamp. The invention allows ready adjustment or re-establishment of another heating schedule to accommodate changes in the fluorescent coating, brought on by short runs of different colored 55 coatings for instance, and to care for indicated

variations in lamp parts and changes in lamp design disturbing the manufacturing schedule.

Other objects and advantages of our invention will appear in the following detailed description of the methods and apparatus disclosed in the drawings.

In the drawings, Figs. 1 to 6 inclusive are side elevations of the lamp parts and associated apparatus in various steps in the course of the treatment and manufacture of a fluorescent lamp; Fig. 7 is a schematic plan view of apparatus for the manufacture of fluorescent lamps in accord with our invention; and Fig. 8 is similar schematic plan view of another embodiment of apparatus for said manufacture.

The first step in the course of the fluorescent lamp manufacture presented in the drawings is the coating of the interior of the tubular bulb 1 as shown in Fig. 1 by flushing a fluid comprising a cellulosic binder having the fluorescent powder in suspension therein over the entire interior surface of the bulb. The coating fluid is preferably discharged from a nozzle 2 introduced in the upper end of the bulb 1 and is directed about the full inner diameter of the tubular bulb 1 by the enlarged end of the valving pin 3. A sufficient quantity of the coating fluid is introduced into the bulb 1 to cause an even flow thereof over the length of the bulb 1 and the draining of a quantity into the trough 4. The bulb 1 is allowed to remain in the position shown until there is no longer any drainage and the coating dries to a point where it will not be disturbed by handling of the bulb 1. Both the coating and drying operations are preferably preformed in automatic high speed apparatus of the type disclosed in United States patent application Patent No. 2,415,512, filed November 16, 1943, by John J. Malloy and assigned to the present assignee. Prior to passing on to the succeeding manufacturing operation the coating must be removed from a very limited area about the rim of both ends of the bulb 1 either by wiping or brushing.

According to our invention the coated bulb 1 is now subject to an operation sealing the electrode carrying mounts 5 and 5' into the opposite ends thereof as shown in Figs. 2 and 3. The mounts 5 and 5' are of the usual design having a flared stem tube 6 adapted to close the open ends of the bulb 1 and are preferably sealed therein in apparatus which first seals the mount 5 in one end of the bulb 1 and which then, after the bulb 1 is turned end for end, seals the second mount 5' in the opposite end of said bulb 1. The stem tube 6 of each mount 5 or 5' supports the electrodes of the lamp which consist of a filamentary cathode 7 of coiled metal wire, coated with a still incompletely treated activation material, and wire anodes (not shown) and provides connections to the cathode 7 and anodes through the leading-in wires 8. A passage through the stem tube 6 of both mount 5 and 5', in this particular instance, is connected to a vitreous exhaust tube 9 or 9', as the case may be, so as to permit the exhaustion and insertion of materials into the bulb 1 after mounts 5 and 5' have sealed the ends of said bulb 1. The preferred form of apparatus used in a subsequent operation permits the exhaust tube 9' at one end of the lamp to be very short; however, the length of said tube 9' is not relevant to the proper carrying out of my invention. As shown in Fig. 2 one end of the bulb 1 and the stem tube 6 of mount 5 are sealed together by the flames from burners 10 while a column of air under pressure is established in

the bulb 1 to prevent the flow of exhaust fumes etc. from the flames from entering said bulb 1 by the jet of air directed into said bulb 1 from the nozzle 11 located thereabove. A relative rotative movement is preferably developed between the lamp parts 1 and 8 and the burners 10 to cause an even treatment of the seal. The stem tube 6 of the mount 5' is sealed to the other end of the bulb 1, after it is inverted, by flames from the burners 12 (Fig. 3). In this instance an air pressure is again created in the bulb 1 to prevent the exhaust gases etc. from entering the bulb 1 by a jet of air directed into the end of the exhaust tube 9 from the nozzle 13.

Apparatus for sealing the stem tubes 6 into the ends of the bulb 1 may be that disclosed in United States patent application Patent No. 2,434,664, F. J. Malloy, filed November 9, 1942, with such modifications therein to produce air pressure in the bulb 1 during the sealing operation as disclosed in United States patent application Serial No. 530,952, R. H. Stuart, filed April 14, 1944. Both of the above patent applications are assigned to the assignee of the present invention.

The following steps in the instance disclosed in Figs. 4, 5, and 6 in the manufacture of a fluorescent lamp are performed while in a somewhat separate portion of apparatus in which the now

completely assembled lamp 14 is held in a head 15 and by which said lamp 14 is advanced into operative relation with certain other apparatus by the regular indexing movements thereof. The head 15 provides a port corresponding to that in the usual exhausting apparatus for holding and making a gas-tight connection to the exhaust tube 9 which exhaust tube 9 is upon insertion of lamp 14 into the head 15 directed through the conical central opening in the washer 16 and the rubber washer 17 to the extent permitted by the opening in the insert 18. After the exhaust tube 9 takes its proper relation in the head 15, the arm 19 is turned so as to screw the cap 20 further onto the body 21 of the head 15 and compresses the rubber washer 17 thereby causing said exhaust tube 9 to be gripped and held, and a leak-proof connection is made to said lamp 14. Additional means are also provided in the pairs of jaws 54 and 55 for gripping and holding the bulb 1 in proper relation in the head 15 to avoid strain on the exhaust tube 9 during the movements thereof which advance the lamp 14 into operative relation to apparatus at a sequence of work stations for the further treatment thereof.

The head 15 takes a course of movement which first causes the lamp 14 to be introduced into an oven 22 (Fig. 4) maintained at sufficiently high temperature to burn out the binder of the coating on the inner surface of the bulb 1 and cause the dissipation and extraction of the occluded gases from the bulb 1 and other parts of the lamp 14. The temperature and length of the heat treatment is so limited as to prevent any over treatment producing a reduction in the efficiency of the particular fluorescent material on the inner surface of the bulb 1. The current fluorescent phosphors can effectively be treated in the temperature range between 400 and 600° C. and for an interval between ten and one minutes, the lower temperature range and longer period of treatment being preferred although a higher temperature and short period of treatment are sufficiently controllable to prevent any critical limit of treatment to be avoided. The heat treatment of the lamp causes the interior of the lamp to

become contaminated with the products of the burning of the binder in the fluorescent coating and such gases etc. that are driven from the lamp parts which products, gases and other foreign materials are caused to be exhausted from the lamp 14 by the flow of a gaseous medium into the exhaust tube 9 at one end of the lamp and out the exhaust tube 9' at the other end thereof. In this particular instance the discharge of the foreign materials is brought about by the very gradual flow of air from the exhaust head 15 to the lamp through the exhaust tube 9 and a corresponding outward flow of the air mixed with the foreign material through the exhaust tube 9' at the opposite end of the lamp. A flow of air through the lamp sufficiently large to displace the volume therein three times is usually preferred. The heat treatment is terminated by the motion of the head 15 which carries the lamp 14 from the oven 22 and which causes the air connection to be separated from the head 15 terminating the flow of air through the lamp 14.

The lamp 14 is now by further movement of the head 15 positioned in operative relation to apparatus for tipping-off the exhaust tube 9' which apparatus as shown in Fig. 5 provides the burners 23 and 24 for heating and fusing the ends of said exhaust tube 9' into a solid end or tip. The only remaining opening to the interior of the lamp is then the exhaust tube 9 which is connected to the head 15.

Succeeding operations to the lamp 14 provide for the exhausting, activation of the cathodes 7, the flushing, the final exhausting, the filling and the tipping-off of the exhaust tube 9 in that order and as represented by Figs. 5 and 6. The initial exhausting takes place as soon after the baking operation as possible and is the result of another connection made to the lamp 14 through the head 15 by means such as a rotary valve (not shown) which permits various connections to be made thereto for the required periods of time. The exhausting operation can be started during the tipping-off of the tube 9', if desired, and continue for a relatively long period, during the immediate portion of which the lamp may again be heated to cause liberation of still additional gases etc. included in the lamp parts and during which period it is connected to sources of electrical energy for causing the heating and consequent activation of the coated cathode at each end thereof. The electrical connections are made through a wiping contact made by the leads 8 at both ends of the lamp 14 with the contact strips 25 located adjacent the path of movement of the lamp 14 and head 15 and are made for a sufficient period to cause the coating materials, such as barium carbonate on the cathodes 7, to be changed to oxides having the desired electron emissive properties. Before the activation of the cathodes is complete, the lamp 14 is flushed by the admission through the head 15 of a quantity of an inert gas, such as nitrogen, or final filling gas and/or a quantity of mercury and then reconnecting said head 15 to another exhaust line. The electrical connections to the lamp 14 are preferably discontinued during and directly after the flushing operation and are remade again thereafter to assist still further in the complete exhaustion and treatment of the lamp 14. It is also deemed preferable to break the electrical connections to the cathodes and to reheat the lamp during a final exhausting operation which completes the treatment thereof.

The subsequent operations in the making of 75 the work stations in the course 29 causing them to

the lamp 14 cause the introduction of a limited quantity of an ionizable gas, such as neon, and a second quantity of mercury, the discharge supporting material, (the first having been drawn out by the exhaust operations) by means (not shown) connected to the lamp through the head 15. The lamp 14 is then sealed off by the flames from the burners 26 and 27 which separate the exhaust tube 9 and tip it off adjacent the end of said lamp 14 completing our method of manufacture.

The complete method of manufacturing the fluorescent lamp 14 as hereinbefore described can best be practiced by high speed automatic apparatus in order that the successful completion of the method can be assured and the resulting advantages hereinbefore referred to realized. The first step in the method, that represented by Fig. 1 wherein the fluorescent coating is applied to the interior surface of the bulb 1, is preferably practiced by the apparatus disclosed in United States patent application Serial No. 510,483, filed November 16, 1943, by John J. Malloy. Such apparatus provides for the proper coating of the bulb 1 and drying of said coating under effective controls and contamination prevention conditions.

Succeeding steps in the complete method of manufacturing the fluorescent lamp are preferably performed by apparatus schematically disclosed in Fig. 7 which apparatus effects the sealing of the mounts 5 and 5' in the open ends of the tubular bulb 1 as shown in Figs. 2 and 3. The sealing operations are performed between the bulb 1 and the mounts 5 and 5' while they are retained in heads on the turret 28 of said apparatus and occur along the course 29 of movement of the heads through a series of work stations. The turret 28 and the work stations which are only schematically represented in the drawing correspond to those of the apparatus disclosed in United States patent application Serial No. 465,008, Frank J. Malloy, filed November 9, 1942, and are associated with the sealing apparatus (not shown) corresponding to that of said application and to United States patent application Serial No. 530,952, Raymond H. Stuart, filed April 14, 1944. The mount 5 and bulb 1 are introduced into a head of the turret 28 at work station A and are, during the counterclockwise indexing rotation of said turret 28 which advances said heads along the course 29, sealed together in the manner indicated in Fig. 2. The indexing motion of the turret 28 is the result of the rotation of the drum-type cam 30 on the main drive shaft 31 of the machine which cam 30 engages rollers 32 (only a few of which appear) indirectly connected in the usual manner to the turret 28 and representative of each head thereon. During the rest period of the head, the regularly shaped portion of the cam 30 is located between two of the rollers 32 whereas during the indexing periods one of said rollers 32 is carried into a curve channel in the cam 30 and advanced thereby. Repeated indexing motions of the turret 28 carry the bulb 1 and mount 5 through all of the stations about the turret 28 thereby causing said bulb 1 and mount 5 to be sealed together and finally again advance the head to station A where the bulb 1 is removed from the head and re-inserted in an inverted position together with a second mount 5'. Succeeding indexing movements of the turret 28 advances the bulb 1 and the mount 5' again through

be sealed together as indicated in Fig. 3. The various operations having to do with the insertion, removal and reinsertion of the bulb 1 and the mounts 5 and 5' into the head of the turret 28 attributed to station A can also be performed at the stations adjacent thereto without interfering with normal sealing operations of the apparatus. The rate of index of the apparatus is such that it is most convenient to remove the bulb 1 from a head taking station A and to reinsert said bulb 1 in the next head taking that station. Accordingly, every other head on the turret 28 is used in the first sealing operation and the alternate heads are used in the second sealing operation. The final sealing operation is complete when the now unitary combination of bulb 1 and mounts 5 and 5' take station B in the course of their second passage through the work stations and in this form appear as the lamp 14 shown in Fig. 4.

The succeeding lamp making operations of our invention are brought about in an adjacent portion of the apparatus into which the lamp 14 is preferably transferred immediately and in this particular instance, automatically by the mechanism 33. The function of the automatic transferring mechanism 33 is to cause the lamp 14 to be carried to and treated in the next manufacturing step immediately without allowing it to cool sufficiently to permit water vapor and other contamination to condense and react with the interior parts thereof. The lamp 14 is transferred from station B of the sealing portion of our apparatus to station C of another adjacent portion thereof by a pivoting motion of the transferring mechanism 33 about the vertical shaft 34 which motion is timed to carry the transferring mechanism 33 to station B after every other indexing movement of the turret 28 when completely assembled lamps 14 appear at said station. The transferring mechanism 33 is moved into operative relation to station B as the lamp 14 is being indexed into this station so that said index causes the lamp 14 to pass between the stationary jaw 35 attached to arm 36 which is pivoted on the shaft 34 and the movable jaw 37 pivoted on the screw 38 which extends from said stationary jaw 35. At such times, the movable jaw 37 is held at the open position by the link 39 and operating lever 40, the latter of which is pivoted on the screw 41 extending from the arm 36 and takes a position determined by the radial extent of portion 42 of the cam 43 in engagement with the roller 44 on the end of the operating lever 40. The spring 45 located between posts in the arm 36 and the actuating lever 40 causes, through its contracting force, the operating lever 40 to take a position in agreement with the extent of the portion 42 of the cam 43 engaged by the roller 44. The transferring of the lamp 14 is initiated by the counterclockwise rotation of the shaft 34 which carries the portion 42 of the cam 43 from engagement with the roller 44 thereby allowing the jaw 37 to close and grip the bulb 14. The next movement of the transferring mechanism 33 is an upward movement lifting the mount 5' and the exhaust tube 9' at the lower end of the lamp 14 from the confining features of the sealing head at station B and is followed by a counterclockwise swing of the mechanism to the position shown which places the lamp 14 at station C. Both of the last mentioned movements of the transferring mechanism 33 are caused by corresponding movements of the shaft 34 and are transferred to the arm 36 thereof

through friction means (not shown). The transferring mechanism 33 reaches the extent of its swinging movement, the position in which it is shown in Fig. 7, when the stop screw 46 on an ear of the arm 36 engages the stationary post 47 whereupon it again takes a short upward movement, in this instance, inserting the exhaust tube 9 into the head 15 at station C to the extent shown in Fig. 4. Still further rotation of the shaft 34 carries the raised portion 48 of the cam 43 against the roller 44 on the actuating lever 40 causing the mechanism 33 to release the lamp 14. The return swing of the transferring mechanism 33 carrying it to station B as previously described occurs at a time when the indexing motion of the turret 49 (only a fragment appearing in Fig. 7) which supports head 15 (Fig. 4) carries the lamp 14 from the jaws 35 and 37 of said transferring mechanism 33 and is produced by a clockwise rotation of the shaft 34 which moves the arm 36 to a position where the stop screw 50 on an ear of said arm 36 engages the stationary post 47. After that position (station B) is reached, the further rotation of shaft 34 turns the cam 43 so that said jaws 35 and 37 are closed by movement of the raised portion 48 of said cam 43 from engagement with the roller 44 on actuating lever 40 and then are opened by the advancement of the raised portion 42 of said cam 43 into engagement with the roller 44. The transferring mechanism 33 is also moved down to its original elevation during the return swing thereof by a corresponding movement of the shaft 34. As hereinbefore noted the entire operation of the transferring mechanism 33 is dependent on the movement of the shaft 34, the actuation of which in turn depends on means (not shown) of usual form corresponding to other similar means of the sealing portion of our apparatus and in this particular instance engaging the main drive shaft 51 of that portion of our apparatus associated with station C. The main drive shaft 51 is also the means of turning the drive shaft 31 of the sealing portion of our apparatus to which it is coupled by the gears 52 and 53 and rotates at half the speed of said shaft 31 to actuate the transferring mechanism 33 and the so far undescribed apparatus at station C in proper timed intervals with respect thereto.

The further treatment of the lamp 14 as previously described in the method takes place while said lamp 14 remains connected to the head 15 of the apparatus presented at station C which head 15 and apparatus associated with said treatment correspond very closely with the apparatus disclosed in detail in United States Patent 2,247,513, A. J. Marshaus, July 1, 1941, and only schematically shown in the present connection in Fig. 7. The lamp 14 is held in the head 15 (Fig. 4) by the exhaust port engaging the exhaust tube 9 and by pairs of jaws 54 and 55 gripping the bulb 1. The head 15 is one of plurality mounted near the periphery of the turret 49 as shown at other stations adjacent station C and carries the lamp 14 through work stations along a course of movement determined by the indexing movements of the supporting turret 49 which is indexed in a counterclockwise direction in a regular manner. Each head 15 about the turret 49 is represented by a roller 56 in a common form of indexing means and is advanced by such rotation of the main drive shaft 51 as carries one of said rollers 56 into the curved channel in cam 57 and finally to the former position of the preceding roller 56. The regular form of the remainder

of the cam 57 fits relatively tight between two of the rollers 56 during the further rotation of the cam 57 and keeps the turret 49 and head 15 in a definite position during said interval.

Repeated indexing movements of the turret 49 and head 15 carry said lamp 14 through several stations and finally to a station within the oven 22 and produce a corresponding rotation of the rotary valve 58 and alignment of passages therein, to which said head 15 is connected through the piping 59. At such times, the lamp 14 is subjected to the heat of the oven 22 which is maintained at a sufficiently high temperature to burn out the binding material and drive out such occluded gases and other contamination contained within the lamp parts and is, through the aligned passages in the rotary valve 58, subjected to the flushing effect of air forced into it from a source (not shown) through said passages piping 59, head 15, and exhaust tube 9. The air and contamination are exhausted or discharged out the exhaust tube 9' at the opposite end of said lamp 14. Succeeding indexing movements of the head 15 continue the treatment of the lamp 14 as the oven 22 extends along the course of movement thereof and the passages within the rotary valve 58 have an arcuate form which continues the air connection to the head 15 therethrough.

The heating and flushing operations to the lamp 14 are terminated by the index of the head 15 beyond the oven 22 and to operative relation to the tipping means provided by the burners 23 and 24. At such times the air connection is broken to the head 15 by the rotary valve 58 and another connection is made in a similar manner through the rotary valve 58 and piping 59 which exhausts said lamp 14. The function of the tipping means is to seal off the exhaust tube 9' permanently and to prevent any influx of water vapor and other contamination into the lamp 14 during the immediate operation of the apparatus as would normally occur as the interior of said lamp 14 cools.

A following indexing movement of the turret 49 does not disturb the exhaust connection through the rotary valve 58 but carries the leading-in wires 8 at opposite ends of the lamp 14 into engagement with contact strips 25 at said ends and at opposite sides of the path of movement thereof so that electrical connections are made to each of the leads 8 separately. Other electrical connections (not shown) made to the contact strips 25 causes sufficient electrical potential to be applied across the cathodes 7 at both ends of the lamp 14 to heat them to a temperature causing a coating, such as barium carbonate, thereon to have the proper electron emissive properties. The connections are such that there is no appreciable difference in potential between cathodes 7 at opposite ends of the lamp 14 and no tendency for a discharge to form through the length thereof. The exhaust and electrical connections are retained through several succeeding indexing movements without change and the lamp 14 continues to be exhausted and the cathodes 7 to be activated.

A change in the manufacture occurs when the head 15 indexes into a station where a mercury dispenser (not shown) in combination with the head 15 is positioned in operative relation to stationary actuating means 60 overlying the turret 49 and head 15 and where the leads 8 at both ends of said lamp 14 engage separate sections 61-61 of the contact strips 25. The dispenser is

preferably of the construction and in the combination of apparatus disclosed in the Marshaus Patent 2,247,513 hereinbefore referred to and provides the lamp 14 with a measured quantity of mercury on operation by the actuating means 60 during the period the head 15 remains at the present station. At such times, the actuating means 60 is operated by means (not shown) properly timed with the operations of the entire apparatus by the movements of the drive shaft 51. The movement of the leads 8 into engagement with the sections 61-61 of the contact strips 25 terminates the heating of the cathodes 7 as said sections are insulated from the other sections of the contact strips 25 and from all sources of electricity. The exhausting operation is preferably continued at the present station although in certain instances it may be desirable to interrupt said operation to assure the movement of mercury into the lamp 14.

The succeeding indexing movement of the head 15 carries it from operative relation to the mercury dispenser actuating means 60 and to a station where the leading-in wires 8 at opposite ends of the lamp 14 engage other sections 62-62 of the contact strips 25 which apply full operating voltage to the cathodes 7. As before, the exhaust connection is continued through the piping 59 and the rotary valve 58.

The following two stations are occupied by still other sections 63-63 of the contact strips 25 which are connected to a source of electricity such that full operating potential is applied across the cathodes 7 and the anodes (not shown) of the mounts 5 and 5' at both ends of the lamp 14 and an arc soon strikes through the full length thereof between a cathode 7 and the opposite anodes. The exhausting of the lamp 14 continues as at the preceding stations with the result that a portion of the vapor created by the mercury therein is withdrawn effecting a flush and acceleration of the exhaustion of the lamp 14.

All electrical connections to the lamp 14 are broken by the indexing movement of the head 15 which advances it beyond the ends of the contact strips 25, a movement which in this particular instance again causes the lamp 14 to be advanced to a station within an oven 64 and to be heated. The exhaust connection to the lamp 14 is continued during the movement to remove the occluded gases and other materials detrimental to lamp life which are released from said lamp 14 by the present head treatment. The heating and exhausting treatments also continue through succeeding indexing intervals and thoroughly clean the lamp 14 of all exhaustible materials by the time the head 15 is advanced to the last station within the oven 64. In the course of the movement to the last mentioned station, the rotary valve 58 is turned so that it breaks the exhaust connection to the lamp 14 and makes another connection, also completed through the piping 59, which causes the admittance of a specific amount of an ionizable gas giving the lamp 14 the required characteristics. A second mercury dispenser actuating means 65 is located at the last station occupied by the oven 64 and in operation releases the required dosage of mercury, the discharge supporting material of the specific lamp 14, to the head 15 which mercury is assisted in its movement through the exhaust tube 9 and into the lamp 14 by the influx of gas thereinto. In certain instances, the lamp 14 may retain sufficient heat from its treatment in the oven 22 so that the heating operation produced by oven 64

is not required. In such instances the oven 64 is not provided in the present combination of apparatus.

The next indexing movement of the head 15 which carries the lamp 14 clear of the oven 64 interrupts the gas-admitting connection made to the lamp 14 through the rotary valve 58 and carries said lamp 14 into operative relation to the tipping-off device 66 located at the next station. The function of this device 66 is to seal the lamp 14 following the final treatment and introduction of the gas and mercury filling therein by fusing and tipping-off the exhaust tube 9 by which it is connected to the upper part of the head 15. The exhaust tube 9 is stretched in the tipping-off operation by a longitudinal movement of the lamp 14 which is then entirely supported by the jaws 54 and 55 of the head 15 and is separated from the stub of the exhaust tube 9 retained in the upper part thereof. After completion of the tipping-off operation and the disengagement of the device 66, the head 15 is indexed in turn through two succeeding stations which are unoccupied by apparatus and allow the completed lamp 14 and the stub of the exhaust tube 9 to be removed from the apparatus. The index of the head 15 beyond these unloading stations brings the head 15 again into station C and starts it on a succeeding cycle of operations like that just described.

The embodiment of our apparatus schematic disclosed in Fig. 8 separates the greater portion of the heating treatment apparatus from the exhaust and filling apparatus thereby reducing the injurious effect of the heat on the rubber parts thereof. The present apparatus also provides a higher possible rate of production and allows longer periods of heat treatment than that previously described and such other advantages that will appear in the description thereof which follows. As in the previously described apparatus, the bulb 1 and mounts 5 and 5' are sealed together to form the lamp 14 in apparatus arranged at work stations about an indexed turret 67 in the manner disclosed in United States patent applications Serial No. 465,008, F. J. Malloy, filed November 9, 1942, and Serial No. 530,952, R. H. Stuart, filed April 14, 1944, hereinbefore referred to. The bulb 1 and mount 5 are manually introduced in a head 68 on the turret 67 at either stations D or E and are brought into operative relation to the burners 69 located at various work stations in the course of the movements of said turret 67. Air nozzles 70 are provided at the first six stations occupied by the burners 69 to direct air into upper end of the bulb 1, before it becomes sealed to the mount 5, to prevent the exhaust gases given off by the flames from said burners 69 from entering the bulb 1. The motion of the turret 67 carries the sealed bulb 1 and mount 5 finally to stations F and G which are unoccupied by other apparatus and which are used in the manual removal of the unitary bulb 1 and mount 5. The mount 5' is sealed over the open end of the bulb 1 in a second passage through the work stations about the turret 67 during which the air nozzles 70 direct air into the lamp through the upper exhaust tube 9 after said bulb 1 is turned end-for-end and reinserted together with the mount 5' into the head 68 at either station D or E. As in the manufacture of the lamp in the previously described apparatus, the bulb 1 and mount 5 are preferably introduced into certain alternate heads 68 on the turret 67 and the bulb 1 and mount 5' are inserted in the inbetween heads 68 so that each of said last mentioned heads 68 advances a completely sealed lamp 14 to sta-

tion H after passing through the work stations occupied by the sealing burners 69.

The lamp 14 is removed from the head 68 at station H by the automatic transferring mechanism 70 (corresponding to such mechanism in combination with the apparatus in Fig. 7) which is driven from the same source (not shown) as the turret 67 in order to cause it to operate every other time a head 68 advances to said station and a completely sealed lamp 14 takes said station. The transferring mechanism 70 is operated about the vertical shaft 71, by which it is controlled, and takes a vertical upward motion separating the mount 5' from the head 68 of the sealing apparatus, swings to the delivery position shown, releases the lamp 14 and returns to the original position at station H at proper intervals to avoid interference with the movements of the lamp 14 and apparatus at both the receiving and delivery stations. The release of the lamp 14 is effected through the movements of the jaw 72 which separates from the lamp 14 sufficiently to allow the mechanism 70 to make the return swing without disturbing the lamp 14 however the mechanism 70 must take station H prior to the movements of the succeeding lamp 14 to prevent the stationary jaw 73 from interfering therewith.

The lamp 14 transferred by the mechanism 70 is introduced in a head 74 on the turret 75 which provides for the advancement thereof in indexing movements in a counter clockwise direction through another series of work stations and is held in place in the head 74 by any suitable gripping means. The indexing movement of the turret 75 is effected by means (not shown) like the corresponding means shown schematically in Fig. 7 which means is operated by the main driving means (not shown) also operating the sealing turret 67 and all other portions of the apparatus. The course of movements of the head 74 carry the lamp 14 into the oven 76 which is maintained at a sufficiently high temperature to cause the lamp 14 to be heated to a degree causing the binder of the fluorescent coating to burn so as to be separated therefrom. The increase in the temperature of the lamp 14 occurs quite rapidly and the burning is in progress when said lamp 14 is advanced below the first of a series of nozzles 77 which are located at succeeding stations and which direct a stream of air into the upper end of the exhaust tube 9. A corresponding discharge of air occurs from the exhaust tube 9' at the bottom of the lamp 14 so that a slight current of air passes through the length of the lamp 14 flushing the combustion products therefrom. The combustion products and such other exhaustible contamination within the lamp are substantially all removed therefrom by the time the indexing movements carry said lamp 14 from below the last air nozzle 77 and no means are provided for continuing circulation of air during the movements of said lamp 14 through the still other work stations within the oven 76. The lamp 14 is finally advanced beyond the oven 76 and to work station J where it is taken from the head 74 on turret 75 and transferred to still another portion of the apparatus. As in the transfer of the lamp 14 from the sealing apparatus herein associated with the turret 67 to the heating apparatus associated with the turret 75, the present transfer of the lamp 14 takes place without causing any appreciable interruption of the lamp manufacturing operations and consequently allows no appreciable time for the heated lamp parts to cool and absorb moisture and other contamination.

The present transfer of the lamp 14 from sta-

tion J is effected by the mechanism 11 which swings about the vertical shaft 78 to operative relation with said station during the index of turret 75 so that the lamp 14 is carried into the pocket in the stationary jaw 79 thereof. The movable jaw 80 of the transfer mechanism 11 is then caused to grip the lamp 14 through rotation of the shaft 78 and cam 81 in a manner described in connection with the other transfer mechanisms and is swung to the delivery position in which it is shown where said lamp 14 is positioned in proper alignment with the head 15'. A following upward movement of the transfer mechanism 11 inserts the exhaust tube 9 at the top of the lamp 14 into the head 15' which corresponds to that shown in Fig. 4 whereupon jaws (shown at 54' and 55' at an adjacent station) of the head 15' close on the lamp 14 and grip it. The remainder of the cycle of operation of the transfer mechanism 11 is completed by the opening motion of the movable jaw 80 and the return swing of the mechanism 11 which carries it away from the head 15' and immediately to operative relation to a head 14 of the previously described apparatus in a succeeding cycle of operation.

The portion of our apparatus receiving the lamp 14 and heretofore referred to only in connection with the head 15' provides for the exhausting, further treatment, filling and final sealing of the lamp 14 and is essentially that disclosed in United States Patent 2,247,513 hereinbefore referred to. The various operations of the apparatus occur during the indexing movements of the head 15' to work stations to which the head 15' is carried by the turret 49' (only partially shown) which motion is produced in the turret 49' by the main driving means (not shown) in order to be in synchronism with the other parts of the apparatus. The indexing movements of the head 15' first bring the lamp 14 to a station where the exhaust tube 9' at the lower end of the lamp 14 is sealed off by the flames from the burners 23' and 24' in the manner described in connection with Fig. 5 and then advance it to another station where the lamp 14 is heated by the oven 82 and is exhausted by means connected thereto through the head 15' and rotary valve 83. The heat treatment rids the occluded gases from the parts of the lamp 14 so that they can be removed therefrom by the exhaust and is succeeded, when the indexing movements of the turret 49' carry the lamp 14 beyond the oven 82, by treatments to the cathodes 1 at opposite ends of the lamp 14 produced by the passage of electricity through said cathodes 1, the results of wiping-connections made to the contact bars 25' by the leading-in wires 8. The treatment to the cathodes 1 consists in the heating thereof by electricity to cause the coating thereon to change to an oxide having electron emissive properties and initiates a course of treatment duplicating that performed in exactly the same manner in the apparatus shown in Fig. 7. The exhaust and cathode treatment continue during the succeeding indexing movements of the head 15' without interruption until the head 15' passes to a station where it is located below the mercury dispenser actuating means 60' and the leading-in wires 8 are brought into engagement with the sections 61' of the contact strips 25'. At this station, the automatic operation of the dispenser actuating means 60' causes a controlled quantity of mercury to be discharged through the head 15' and the exhaust tube 9 to the interior of the lamp 14 and the en-

gagement with the sections 61' of the contact strip 25' interrupts the cathode treatments since said sections 61' are not connected to any source of electricity. The exhaust connection continues as in the previous stations. Further indexing movements of the head 15' carry the leading-in wires 8 into engagement with the sections 62' of the contact strips 25' and then into engagement with the sections 63' thereof thereby causing further heat treatment of the cathodes 1 and a temporary end-to-end discharge in the lamp 14. Still further indexing movements of the head 15' advance the lamp 14 into the oven 64', breaks the exhaust connection thereto through the rotary valve 83 and causes the proper gas and mercury filling to enter the lamp 14 through the adjustment of the rotary valve 83 and the operation of the dispenser actuating means 65'. Final treatment to the lamp 14 occurs when it is carried into operative relation to the tipping-off device 66' which seals the lamp 14 by fusing an intermediate section of the exhaust tube 9 into a permanent tip. The lamp 14 and the remainder of the exhaust tube 9 are removed from the jaws 54' and 55' and the upper portion of the head 15' at the two following work stations which are the final stations taken by the head 15' in one cycle of operation of the apparatus. The head 15' begins another repeated cycle of operation in the next index which carries it into position to receive another lamp 14 from the transfer mechanism.

What we claim as new and desire to secure by Letters Patent of the United States is:

1. The method of manufacturing electric fluorescent lamps in a sequence of operations which comprises heating a partially manufactured lamp, having a bulb with a coating of a fluorescent material and a binder on the interior thereof and having a passage through to said interior, to cause the binder to burn and be separated from the coating, exhausting the lamp through the passage directly following the heating operation before said lamp cools appreciably to remove all exhaustible materials therefrom, introducing into the lamp immediately after the final exhaustion thereof an ionizable gas and a discharge supporting material through the passage, and thereafter sealing the passage in the lamp to permanently seal said lamp.
2. The method of manufacturing electric fluorescent lamps in a sequence of operations which comprises immersing a partially manufactured lamp having a bulb with a coating of a fluorescent material and a binder on the interior thereof and having a passage through to said interior in a heated gaseous atmosphere to cause the binder to burn and be separated from the coating, exhausting the lamp through the passage directly following the heating operation before said lamp cools appreciably to remove all exhaustible materials therefrom, introducing into the lamp immediately after the final exhaustion thereof an ionizable gas and a discharge supporting material through the passage, and thereafter sealing the passage in the lamp to permanently seal said lamp.
3. The method of manufacturing electric fluorescent lamps in a sequence of operations which comprises heating a partially manufactured lamp having a bulb with a coating of a fluorescent material and a binder on the interior thereof and having a passage through to said interior to cause the binder to burn and be separated from the coating, exhausting the lamp during the heat treatment thereof to remove the combustion

products and the occluded elements released by the heat treatment therefrom, directly thereafter and before said lamp cools appreciably more completely exhausting the lamp to remove the atmosphere from said lamp, introducing into the lamp immediately after the final exhaustion thereof an ionizable gas and a discharge supporting material through the passage, and thereafter sealing the passage in the lamp to permanently seal said lamp.

4. The method of manufacturing electric fluorescent lamps in a sequence of operations which comprises heating a partially manufactured lamp, having a bulb with a coating of a fluorescent material and a binder on the interior thereof and having electrode mounts with passages therethrough to said interior at opposite ends of said bulb, to cause the binder to burn and be separated from the coating, and concomitantly flushing the interior of the lamp to remove the combustion products with a gaseous medium introduced in and exhausted from said lamp through the passages in the electrode mounts at opposite ends thereof.

5. The method of manufacturing electric fluorescent lamps in a sequence of operations which comprises heating a partially manufactured lamp having a tubular bulb with a coating of a fluorescent material and a binder on the interior thereof and having passages through to said interior at opposite ends of said bulb to cause the binder to burn and be separated from the coating, concomitantly flushing the interior of the lamp to remove the combustion products with a gaseous medium introduced in and exhausted from said lamp through the passages at opposite ends thereof, sealing the passage at one end of the lamp and exhausting the interior of the lamp through the other passage directly following the heating operation before said lamp cools appreciably to remove the atmosphere and thereafter introducing an ionizable gas and a discharge supporting material therein through the said other passage in said lamp, and sealing the last mentioned passage in the lamp to permanently seal said lamp.

6. The method of manufacturing electric fluorescent lamps in a sequence of operations which comprises heating a partially manufactured lamp, having a tubular bulb with a coating of a fluorescent material and a binder on the interior thereof and having electrode mounts with exhaust tubes communicating with passages through to said interior sealed to the opposite ends of said bulb, to cause the binder to burn and be separated from the coating, flushing the interior of the lamp to remove the combustion products during the heating operation with a gaseous medium introduced in and exhausted from said lamp through the exhaust tubes at opposite ends thereof, sealing the exhaust tube at one end of the lamp and exhausting the interior of the lamp through the open exhaust tube directly after the heat treatment while said lamp is still at nearly maximum temperature to remove the atmosphere, introducing an ionizable gas and a discharge supporting material in the lamp through the last mentioned exhaust tube to give said lamp the desired operating characteristics, and sealing the last mentioned exhaust tube to permanently seal the lamp.

7. The method of manufacturing electric fluorescent lamps in a sequence of operations which comprises heating a partially manufactured lamp, having a tubular bulb with a coating of a

fluorescent material and a binder on the interior thereof and having electrode mounts with unactivated cathodes theron sealed to the opposite ends of said bulb, one of said mounts having a

5 passage therethrough giving access to said interior, said heating being sufficient to cause the binder to burn and become separated from the coating, exhausting the atmosphere and other materials from the interior of the lamp through

10 the passage in the electrode mount directly following the heating operation before said lamp cools appreciably, connecting a source of electricity to the electrode mounts to heat and cause activation of the cathodes thereof during said exhaust operation, introducing an ionizable gas and a discharge supporting material into the lamp through the passage in the mount to give said lamp the desired operating characteristics, and thereafter sealing the passage to permanently

20 seal the lamp.

8. The method of manufacturing electric fluorescent lamps in a continuous uninterrupted sequence of operations which comprises sealing electrode mounts to opposite ends of a tubular

25 bulb provided with a coating of a fluorescent material and a binder, one of said mounts having an exhaust passage therethrough connected to an exhaust tube and giving access to the interior of the lamp, heating the full length of the

30 lamp to cause the binder in the coating to burn and be separated from the bulb and the occluded gas to be driven therefrom, exhausting the atmosphere and other materials from the interior of the lamp by means of the exhaust tube directly

35 following the heating operation before the lamp cools appreciably, introducing an ionizable gas and discharge supporting material into the lamp through the exhaust tube to give said lamp the desired operating characteristics, and sealing the exhaust tube to permanently seal the lamp.

9. The method of manufacturing electric fluorescent lamps in a sequence of operations which comprises applying to the inner surface of an

45 open ended tubular bulb a coating of a fluorescent material and a binder, sealing electrode mounts to the opposite ends of the bulb, one of said mounts having a passage therethrough connected to an exhaust tube and giving access to

50 the interior of the lamp, heating the lamp to cause the binder in the coating to burn and be driven from the bulb, exhausting the atmosphere and other materials from the interior of the lamp by means of the exhaust tube directly following the heating operation before the lamp cools ap-

55 preciably, introducing an ionizable gas and a discharge supporting material into the lamp through the exhaust tube to give the lamp the desired operating characteristics, and thereafter sealing the exhaust tube to permanently seal the lamp.

10. The method of manufacturing electric fluorescent lamps in a sequence of operations which comprises applying to the inner surface of an open ended tubular bulb a coating of a fluorescent material and a binder, sealing electrode mounts having exhaust passages therethrough connected to exhaust tubes to opposite ends of the bulb, heating the lamp to cause the binder in the coating to burn and be separated from the bulb, concomitantly flushing the lamp with air directed into the exhaust tube at one end thereof and exhausted together with the products of combustion from the exhaust tube at the

60 70 75 opposite end thereof, sealing the exhaust tube

at one end of the lamp and exhausting the lamp through the other exhaust tube directly following the heating operation before said lamp cools appreciably, and then filling the lamp with the proper quantities of ionizable gas and a discharge supporting material through the said other exhaust tube, and sealing the last mentioned exhaust tube to permanently seal the lamp.

11. The method of manufacturing electric fluorescent lamps in a sequence of operations which comprises applying to the inner surface of an open ended tubular bulb a coating of a fluorescent material and a binder, sealing electrode mounts having exhaust passages therethrough connected to exhaust tubes to opposite ends of the bulb in turn, directing a jet of air alternately into the open end of the bulb and into the exhaust tube opposite from the seal during respective sealing operations to increase the air pressure in the bulb and prevent the entrance of contaminating gases thereinto during formation of the seal, heating the lamp to cause the binder in the coating to burn and be separated from the bulb, concomitantly flushing the lamp with air directed into the exhaust tube at one end thereof and exhausting it together with the products of combustion from the exhaust tube at the other end of the lamp, sealing the exhaust tube at one end of the lamp and exhausting the lamp through the other exhaust tube directly following the heating operation before said lamp cools appreciably, and then filling the lamp with the proper quantities of ionizable gas and a discharge supporting material through said other exhaust tube, and sealing the last mentioned exhaust tube to permanently seal the lamp.

12. The method of manufacturing electric fluorescent lamps in a sequence of operations which comprises flushing the inner surface of an open ended tubular bulb with a coating fluid of a fluorescent material and a binder, allowing the excess fluid to drain from the bulb and the remaining coating to dry, sealing electrode mounts having exhaust passages connected to exhaust tubes to opposite ends of the bulb to complete the lamp structure, immediately heating the lamp to cause the binder in the coating to burn and be separated from the bulb, flushing the lamp during the heating operation with air directed into the exhaust tube at one end thereof and exhausting together with the combustion products from the exhaust tube at the other end thereof, sealing the exhaust tube at one end of the lamp before said lamp cools appreciably, immediately exhausting the lamp through the remaining open exhaust tube before said lamp cools appreciably, filling the lamp with an ionizable gas and a discharge supporting material, and sealing the last mentioned exhaust tube to permanently seal the lamp.

13. Apparatus for manufacturing electric fluorescent lamps comprising means for carrying a lamp, having a coating of a fluorescent material and a binder on the interior thereof and a pair of exhaust tubes communicating with said interior, in a continuous course of movement to a sequence of work stations, an oven located at one of the stations for heating the lamp to cause the binder to burn and separate from the fluorescent material, means at the last mentioned station for directing air through one of the exhaust tubes of the lamp to flush the combustion products within the interior out through the other exhaust tube thereof, means at an immediately succeeding station for fusing and sealing one of

the exhaust tubes, means at succeeding stations for making a gas-tight connection to the unsealed exhaust tube and causing the exhaustion and then the introduction of an ionizable gas and a discharge supporting material into the lamp directly after said lamp is heated in the oven and before it cools appreciably, and means at the latter of the last mentioned stations for fusing and sealing the last mentioned exhaust tube to seal and complete the manufacture of the lamp.

14. Apparatus for manufacturing electric fluorescent lamps comprising a head for holding a lamp, having a coating of a fluorescent material and a binder on the interior thereof, and making a gas-tight connection to one of a pair of exhaust tubes communicating with said interior, a carrier for supporting and advancing the head in a continuous course of movement to a sequence of work stations, an oven located at one of the stations for heating the lamp to cause the binder to burn and separate from the fluorescent material, means connected to the head at the last mentioned station for causing air to be directed through the exhaust tube engaged thereby to the interior of the lamp to flush the combustion products within the interior out the other exhaust tube thereof, means at an immediately succeeding station for fusing and sealing the last mentioned exhaust tube, means connected to the head at succeeding stations for causing the exhaustion and then the introduction of an ionizable gas and a discharge supporting material into the lamp directly after said lamp is heated in the oven and before it cools appreciably, and means at another succeeding station for fusing and sealing the last mentioned exhaust tube to seal and complete the manufacture of the lamp.

15. Apparatus for manufacturing electric fluorescent lamps comprising a carrier for advancing a lamp, having a coating of a fluorescent material and a binder on the interior thereof and a pair of exhaust tubes communicating with said interior, in a course of movement, an oven located along the course of movement for heating the lamp to cause the binder to burn and separate from the fluorescent material, means in combination with the oven for directing air through one of the exhaust tubes of the lamp to flush the combustion products from the interior and out the other exhaust tube thereof, a second carrier for holding and advancing the lamp to a sequence of work stations located adjacent the first carrier, a transferring mechanism for removing the lamp advanced beyond the oven from the first carrier and immediately inserting it in the second carrier, means at a station of the second carrier for fusing and sealing one of the exhaust tubes, means for making a gas-tight connection to the unsealed exhaust tube at succeeding stations and causing the exhaustion and then the introduction of an ionizable gas and a discharge supporting material into the lamp, and means at the latter of the last mentioned stations for fusing and sealing the last mentioned exhaust tube to seal and complete the manufacture of the lamp.

16. Apparatus for manufacturing electric fluorescent lamps comprising sealing apparatus for fusing electrode mounts having exhaust tubes communicating with passages therethrough to opposite ends of a tubular bulb having a coating of a fluorescent material and a binder on the interior thereof to complete a lamp, means located adjacent the sealing apparatus for carrying a

lamp in a continuous course of movement to a sequence of work stations, transferring mechanism located in operative relation to the sealing apparatus and the last mentioned means for removing the lamp from said sealing apparatus and inserting it in said last mentioned means, an oven located at one of the stations of the last mentioned means for heating the lamp to cause the binder to burn and separate from the fluorescent material, means at the last mentioned station for directing air through one of the exhaust tubes of the lamp to flush the combustion products within the interior out through the other exhaust tube thereof, means at a succeeding station for fusing and sealing one of the exhaust tubes, means for making a gas-tight connection to the unsealed exhaust tube at succeeding stations and causing the exhaustion and then the introduction of an ionizable gas and a discharge supporting material into the lamp, and means at the latter of the last mentioned stations for fusing and sealing the last mentioned exhaust tube to seal and complete the manufacture of the lamp.

17. Apparatus for manufacturing electric fluorescent lamps comprising sealing apparatus for fusing electrode mounts having an exhaust tube communicating with a passage therethrough to opposite ends of a tubular bulb having a coating of a fluorescent material and a binder on the interior thereof, said sealing apparatus comprising means for supporting said bulb and an electrode mount in sealing relation, burners for directing fires against contiguous portions of the bulb and mount to seal them together, means for directing air into the interior of the bulb to prevent the combustion products from entering and contaminating the interior of the lamp, means located adjacent the sealing apparatus for carrying a lamp in a continuous course of movement

to a sequence of work stations, transferring mechanism located in operative relation to the sealing apparatus and the last mentioned means for removing the lamp from said sealing apparatus and inserting it in said last mentioned means, an oven located at one of the stations of the last mentioned means for heating the lamp to cause the binder to burn and separate from the fluorescent material, means at the last mentioned station for directing air through one of the exhaust tubes of the lamp to flush the combustion products within the interior out through the other exhaust tube thereof, means at a succeeding station for fusing and sealing one of the exhaust tubes, means for making a gas-tight connection to the unsealed exhaust tube at succeeding stations and causing the exhaustion and then the introduction of an ionizable gas and a discharge supporting material into the lamp, and means at the latter of the last mentioned stations for fusing and sealing the last mentioned exhaust tube to seal and complete the manufacture of the lamp.
